UNITED STATES PATENT OFFICE

2,495,383

SAFETY DEVICE FOR FIREARMS

Lester F. Mulno, Worcester, Mass., assignor to
 Harrington & Richardson Arms Company,
 Worcester, Mass., a corporation of Massachusetts

Application January 2, 1948, Serial No. 10

4 Claims. (Cl. 89—145)

1

This invention relates to safety devices for firearms.

The principal object of the invention resides in the provision of an extremely easily operable device for holding a breech bolt of a firearm in open condition, so that the firearm may not be accidentally fired.

A further object of the invention resides in the provision of a firearm having a pivoted hook or the like which is movable into the path of an action bar so as to engage the latter at its rearwardmost position, to hold the action bar in said rearwardmost position, said hook being moved into the path of the action bar by means of a spring, and there being provided a hand operated member to engage the hook and hold the same out of the path of the action bar against the action of the spring; and the provision of a device as above described including a connecting lever between the firearm sear and the action bar, said connecting lever being engaged by the hand operated member and depressed out of engagement with the sear upon movement of the member to release the hook spring, whereby the action bar is held in breech open condition of the firearm and, at the same time, the connecting lever is held in safety position.

A still further object of the invention resides in the provision of a firearm having a reciprocating breech bolt, an action bar connected thereto for movement therewith, and a pivoted hook in position to engage the action bar at the rearwardmost point of its travel and latch the same to hold the breech bolt open, said hook having a cam-shaped nose so that when the hook is positioned in the path of the action bar, the latter is enabled to ride over the hook and become latched upon manual retraction of the action bar.

Other objects and advantages of the invention will appear hereinafter.

Reference is to be had to the accompanying drawings in which

Fig. 1 is a longitudinal sectional view through the receiver of a firearm provided with a safety device of the present invention, parts being broken away;

Fig. 2 is a view in elevation of the receiver of a firearm according to the present invention showing the firearm in firing condition, parts being broken away;

Fig. 3 is a view similar to Fig. 2 but showing the firearm in safe condition;

Fig. 4 is a view in elevation of the safety hook; and

Fig. 5 is a top plan view of the same.

2

In the present invention, there is presented a relatively simple but extremely positive safety device for use in firearms having a reciprocating action bar, one example of which is disclosed in the present case and which is also shown in copending application No. 494,660, filed July 14, 1943, now abandoned, and also in Patent No. 2,422,854, July 1, 1947. There are, of course, other firearms to which the present invention may be applied.

In Fig. 1, there is shown a firearm having a barrel 10, a receiver 12, a breech bolt chamber 14, and a reciprocating bolt 16 therein having a firing pin 18. In the particular illustration herein, the breech bolt chamber is provided with a reciprocating hammer 20 having a hammer spring 22 located at one end against a bumper plug 24 closing the chamber 14.

As will be well recognized, the bolt 16, which is shown in breech closed condition in Fig. 1, reciprocates in the chamber 14 and since it carries the firing pin 18 therewith, the firearm cannot be operated unless the breech bolt is in breech closed condition.

An action bar 26, which is spring pressed forwardly to breech bolt closed condition by a spring 28, is connected to the bolt 16 by means of a rear plate 30, which is engaged in the bolt as, for instance, by a slot at 32. The action bar 26 slides in a guide formed by studs 34 and a magazine plate 36 for a magazine holder 38.

A trigger block is shown at 40 pivotally mounting a trigger 42 having a spring 44. Pivoted to the trigger at 46 is a connecting lever 48 having a spring 50 urging the connecting lever into the path of the action bar. Lever 48 is provided with a shoulder 52 adapted to engage a corresponding shoulder on a sear 54, the sear engaging the hammer 20 and holding the same in the Fig. 1 position until the trigger is pulled, moving the lever 48 forwardly and pivoting with it the sear so as to withdraw the same from the hammer to allow the latter to move forwardly under action of the hammer spring to actuate the firing

pin. It will be, of course, obvious that when the bolt retracts, the action bar will depress the lever 48 and allow the sear to return to its active position under influence of the sear spring which is indicated at 56. As so far described, the firing mechanism of the firearm follows the mechanism described in the above noted pending application and patent.

A lever 58 is pivoted at 59 on the trigger block 40 and is provided with a spring in the trigger block indicated at 60, see Figs. 2 and 3, said spring

acting on a lateral projection 62 on lever 58 to normally move the latter upwardly so that a hook at 64 is located in the path of the action bar plate 30 to latch the same in rearwardmost position as indicated in dotted lines in Fig. 3. It will, therefore, be seen that although the firearm may be ready to be fired, it will be merely necessary to retract the action bar to latch the same in breech open condition so that the gun cannot be fired.

A safety lever is indicated at 65, this lever being pivoted at 66 on the trigger block 40 and having an inturned flange 68 in position to engage the underside of the projection 62 and forcibly press the hook lever 58 downwardly to the Fig. 1 position when lever 65 is pivoted to the Fig. 2 position so as to retract the hook 64 out of the path of the action bar 26, thus providing for continued firing of the firearm.

When, however, the lever 65 is moved to the Fig. 3 position, the flange 68 moves out of contact with projection 62 and thereby allows the spring 60 to come into play to resiliently urge the hook lever 58 upwardly to the Fig. 3 position so as to catch the action bar upon rearward movement thereof.

The connecting lever 48 is provided with a stud 70 which is engaged by the flange 68 to depress lever 48 at the same time that the hook lever is allowed to rise thus providing for a double safety feature disconnecting the sear from the trigger, and thus insuring that the firing pin cannot be actuated under any circumstances.

The free end of the hook lever 58 is provided with a cam nose 72 so that the action bar can ride over the hook 64, the spring 60 causing the hook to rise behind the action bar plate 30 to latch the action bar at any time when lever 65 is on safe position, as shown in Fig. 3.

It will be seen that this invention presents a simple and yet extremely effective safety device which holds the breech bolt in open condition as is usually required to indicate that the gun is safe. At the same time, the connecting lever 48 is also immobilized so that the lever 65 produces a double safety feature.

Having thus described my invention and the advantages thereof, I do not wish to be limited to the details herein disclosed otherwise than as set forth in the claims, but what I claim is:

1. Safety device for a firearm having a reciprocable action bar and connected breech bolt comprising movable means in the path of the action bar for selective engagement therewith to hold the same and the bolt in breech open condition, a sear, means to positively move the said movable means out of the path of the action

bar to provide for normal function thereof, and a connecting lever between the action bar and sear, said means disengaging the lever from the action bar.

2. Safety device for a firearm having a reciprocating breech bolt and connected action bar, a hammer, a sear, and a connecting lever between the action bar and sear, comprising a movable means selectively movable into or out of the path of the bar, means on the movable means to engage and stop the action bar when the latter is in the action bar path, and hand operated means to move the movable means, said hand operated means engaging and disconnecting the connecting lever from the sear.

3. Safety device for a firearm having a reciprocating breech bolt and connected action bar, a hammer, a sear, and a connecting lever between the action bar and sear, comprising a movable means selectively movable into or out of the path of the bar, means on the movable means to engage and stop the action bar when the latter is in the action bar path, resilient means moving the movable means into the action bar path, hand

operated means to engage the movable means and retract the same from the action bar path against the action of the resilient means, said hand operated means engaging and moving the connecting lever out of connection with the sear upon actuation of the hand operated means to release the movable means to permit the resilient means to move the movable means into the action bar path.

4. Safety device for firearms comprising a reciprocating breech bolt, an action bar connected thereto, a hammer, a sear, a connecting lever between the sear and the action bar, the latter depressing the lever and disconnecting the sear during rearward motion of the action bar, a pivoted hook to engage and latch the action bar in the rearwardmost position of the latter, a spring urging the hook into the action bar path, and a hand operated element to engage and retract the hook from the action bar path against the action of the spring, said element engaging and disengaging the connecting lever from engagement with the sear upon actuation to release the hook.
